US0D1015430S

(12) **United States Design Patent** (10) Patent No.: **US D1,015,430 S**
(45) Date of Patent: ** *Feb. 20, 2024

(54) **GAMING CONSOLE AND GAMING CONTROLLER SYSTEM**

(71) Applicant: **Intellivision Entertainment LLC**, Irvine, CA (US)

(72) Inventors: **Tommy Tallarico**, San Juan Capistrano, CA (US); **Juan M. Alvarado**, Tustin, CA (US); **André LaMothe**, Austin, TX (US); **Todd Linthicum**, Aliso Viejo, CA (US); **David Slade Simpson**, Aliso Viejo, CA (US)

(*) Notice: This patent is subject to a terminal disclaimer.

(**) Term: **15 Years**

(21) Appl. No.: **29/734,578**

(22) Filed: **May 13, 2020**

(51) LOC (14) Cl. **21-02**
